UNITED STATES PATENT OFFICE.

JAMES W. HAMMETT, OF EUREKA, WEST VIRGINIA.

FILTER.

939,497.

Specification of Letters Patent.

Patented Nov. 9, 1909.

Application filed June 16, 1909. Serial No. 502,608.

To all whom it may concern:

Be it known that I, JAMES W. HAMMETT, of Eureka, in the county of Pleasants and State of West Virginia, have invented certain new and useful Improvements in Filters; and I do hereby declare the following to be a full, clear, and exact description of the invention, such as will enable others skilled in the art to which it appertains to make and use the same.

My invention relates to an improvement in filters, designed to be submerged in the source of water supply, and connected to a pump, whereby the water drawn or forced out by the pump, will be freed of all impurities that can be removed by a sand filter.

My invention consists in air and water pipes communicating with a chamber composed of plates connected by a series of pipes, and also by reinforcing rods, a base, and a body of masonry or concrete in which the reinforcing strips are embedded, the sides or body of the filter having perforations through same for the passage of water to the filter chamber, and covered with gravel and sand through which the water must pass before entering the filter chamber.

My invention further consists in certain details of construction as will be more fully described and pointed out in the claims.

In the accompanying drawings, Figure 1 is a view of the upper and lower plates and connecting pipes and reinforcing connection. Fig. 2 is a view in vertical section of the completed filter. Fig. 3 is a view in horizontal section and Figs. 4 and 5 are views in section of a modified form of filter.

1 represents the cap plate and 2 the base plate connected by a pipe 3 which latter passes through both plates and terminates below the base plate in a nozzle 4, and are also connected by the air pipe 5 and the pump pipe 6. The base plate 2 is provided with upwardly projecting threaded flanges 7 for the attachment of the lower ends of the pipes 5 and 6, and with an opening having threaded wall for attachment of the lower end of the through pipe 3. The upper ends of these pipes all terminate within flanged collars 8 screwed into the cap plate, and communicate with pipes 3^a 5^a and 6^a which extend from a point above the surface

of the water down to the collar 8 and are screwed into the upper threaded ends of said collars. The two plates 1 and 2 are further connected by the reinforcing bars 9, which as shown in Fig. 1, are secured at their lower ends to the base plate 2 and extend outwardly therefrom and are then bent upwardly and inwardly and are secured at their upper ends to the cap plate 1.

In constructing the permanent or fixed filter shown in Figs. 1, 2 and 3, a coffer dam of the proper size is sunk to the bottom of the river bed or other body of water, and after having been freed of water, an excavation of the necessary size is made, after which the skeleton frame work consisting of the cap and base plates 1 and 2, pipes 3, 4 and 5 and reinforcing bars 9 is placed in position on the bottom of the excavation and covered with about two inches of concrete 10, the latter extending out some little distance beyond the reinforcing angle irons. After the concrete base 10 has sufficiently set, I fill the space between the cap plate 1 and the major part of the concrete base 2, but inside of the reinforcing angle bar, with wet sand in the form of a truncated cone, the latter being confined and held in place by a sheet of muslin or other fabric snugly drawn over the surface of the sand, the fabric being greased to prevent the concrete body of the filter from adhering thereto. After the sand core has been thus formed, concrete is deposited over and on the fabric from the concrete base up to the cap plate 1, thus embedding the angle bars 9, which latter reinforce the concrete body or wall of the filter. The thickness of this wall 11 of concrete should be in proportion to the size of the filter, and while it is in a soft state, it is perforated at numerous points, by forcing pointed and greased strips through it, and also through the fabric inclosing the sand core. These strips may be of metal or wood and should be removed as soon as the concrete sets. After the concrete sets, it is covered with graded gravel and sand, the coarse gravel being next to the concrete, and gradually grading down outwardly to sharp sand, the coating of gravel and sand being preferably about three feet in thickness.

Across the top of the filter I form a hood 105 13 of fine mesh non-corrodible wire, and

above hood 13, and attached thereto, is a hood of strong heavy woven wire 14 weighted at its edges by concrete blocks 15, the latter being well out beyond the outer 5 edge of the top of filter body 11.

The hood 14 is covered with sand and gravel to approximately the level of the bed of the river or other body of water, and I prefer to provide at least six inches of gravel 10 and sand above the hoods.

After the concrete has set, the sand core and its fabric covering are removed through an opening in the cap plate, which opening is subsequently closed and sealed.

15 Pipes 5 and 6 are each provided with openings 15^a near the bottom, for the admission of water to the pipe 6 which is connected with the pump, and for the admission of air to the filter chamber through pipes 5^a 20 and 5, the latter being also provided near its top with a hole 16 for the entrance of air to the top of the chamber. The opening 15^a in pipe 5 is also for the passage of water and whatever sediment may have accumulated within the filter, when the latter is flushed by forcing water down through 25 pipe 6.

All of the pipes extend up above the surface of the water and those except the pump 30 pipe 6^a are preferably covered with a wire hood.

In the larger size filters such as I have described, the through pipe may be omitted but in the small sizes which are built above 35 the surface and then submerged, this pipe is necessary. The small sizes, or portable filters may be conical in shape like that shown in Fig. 2, but I prefer to make them cylindrical as shown in Figs. 4 and 5. In constructing 40 this form, I secure the cap plate and base plate by the pipes and straight reinforcing rods, and cover the base plate with a layer of concrete, as in the previous structure. A bag of sand is suspended from the top plate 45 within the space between the three pipes 3-5 and 6 and covering and protecting the openings in the latter, after which the concrete is molded around the pipes and sand bag, and between the cap and base plates, 50 the concrete body being perforated as in the previous construction for the free inflow of water. After the concrete has set sufficiently the sand core and its bag are removed thus leaving a water and air space between the 55 pipes.

The filters may be sufficiently small to be used in a bored well or they may be fixed structures of any desired capacity. The smaller sizes may be sunk in gravel or sand 60 in the bed of a river or other body of water, by lowering the filter onto the bottom and forcing water through the through pipe 3 and nozzle 4, in a manner similar to that employed for sinking piles, and when used

in bored wells, sand may be supplied to the 65 outer side of the filter body by forcing it down through the through pipe, or shoveled in from the top.

It is evident that many slight changes might be resorted to in the relative arrangement of parts shown and described without departing from the spirit and scope of my invention, hence I would have it understood that I do not wish to confine myself to the exact construction and arrangement of parts 75 shown and described, but,

Having fully described my invention what I claim as new and desire to secure by Letters-Patent, is:—

1. A filter comprising cap and base plates 80 and a body wall intermediate the plates, and having holes therein, tie rods connecting the plates and reinforcing the wall, and a plurality of pipes passing through the top plate and communicating with the chamber 85 formed by the plate and body wall.

2. A filter comprising cap and base plates, and a body wall intermediate the plates and having holes through same, tie rods connecting the plates and reinforcing the wall 90 and a plurality of pipes passing through said cap plate, two of said pipes communicating with the filter chamber and the third pipe terminating in a discharge nozzle below the base plate.

3. A submerged filter comprising a body wall provided with perforations, a base plate, a cap plate resting on the body, a plurality of pipes passing through the cap plate and communicating with the filter 100 chamber, a bed of gravel and sand covering the perforated body, and an open work hood located above the cap plate and covered with gravel and sand.

4. A submerged filter comprising a body 105 having numerous perforations thru the same, a flanged base plate, a cap plate, pipes passing through the cap plate and secured to the flanges of the base plate, the said pipes being in open communication with the 110 filter chamber and a bed of gravel and sand covering the perforated body.

5. A submerged filter comprising a top plate, a bottom plate and a built up reinforced and perforated body, the parts reinforcing the body also connecting the top and bottom plates, and a series of pipes passing through the top plate and secured to the base plate, the said pipes communicating with the interior of the filter chamber.

6. A submerged filter comprising a top plate, a base plate, rods connecting the two plates, a built up body connecting the plates and reinforced by the rods connecting the latter, the said body being perforated and covered with gravel and sand, a wire hood covering the top plate and carrying a bed of gravel and sand, the said hood projecting

beyond the top plate and overhanging the gravel and sand covering the body, and pipes passing through the top plate and communicating with the filter chamber.

- 5 7. A submerged filter comprising a cap plate, a base plate, rods connecting the two plates, a built up body connecting the two plates and reinforced by the connecting rods, the said body being perforated and
10 covered with gravel and sand, a wire hood covering the cap plate and anchored to the bed of the stream, the said hood carrying

a mass of gravel and sand, the latter extending into the vertical plane of the filter covering of the body, and pipes extending from 15 above the surface of the water into the filter chamber.

In testimony whereof, I have signed this specification in the presence of two subscribing witnesses.

JAMES W. HAMMETT.
